UNITED STATES PATENT OFFICE.

HARRY L. WHISINNAND, OF HERMES, COLORADO.

PEN AND PENCIL HOLDER.

1,263,975.

Specification of Letters Patent. Patented Apr. 23, 1918.

Application filed April 10, 1917. Serial No. 161,052.

To all whom it may concern:

Be it known that I, HARRY L. WHISINNAND, a citizen of the United States, residing at Hermes, in the county of Kit Carson 5 and State of Colorado, have invented new and useful Improvements in Pen and Pencil Holders, of which the following is a specification.

This invention comprehends the provision of a pen and pencil holder by means of which a number of such articles may be conveniently carried on the person with the least possibility of loss of the same, the invention providing a unique and novel construction of a device of this character.

In carrying out the invention I aim to provide a device of the above mentioned character wherein a plurality of pencils or pens of different sizes can be conveniently accommodated and properly supported.

Another important object of the invention resides in the provision of a novel construction of means whereby the device may be securely attached to the clothes of the user.

The nature and advantages of the invention will be better understood from the following detail description when read in connection with the accompanying drawing, the invention residing in the construction, combination and arrangement of parts as claimed.

In the drawing forming part of this specification like numerals of reference indicate similar parts in the several views and wherein:—

Figure 1 is a front elevation of the device constructed in accordance with my invention.

Fig. 2 is a rear elevation.

Fig. 3 is a sectional view taken on line 3—3 of Fig. 1.

Fig. 4 is a view of the device showing the fastening means in inactive position, and the flexible tape removed.

Fig. 5 is a detail view of one of the fastening elements.

The device constructed in accordance with my invention preferably embodies an elongated plate or member 10 which may be constructed from any suitable material, preferably metal, the plate being provided with spaced pairs of transversely disposed slots, each pair of slots being indicated at 11. Threaded through the slots is an elastic tape 12 being suitably secured to the plate 10, the

tape being preferably threaded in the manner illustrated so as to provide separate or independent article receiving loops 13 at one side of the plate. It might here be stated that the number of article receiving loops 60 largely depends upon the size of the plate 10, and this may be varied without departing from the spirit of the invention. It will be noted that the pairs of slots 11 are not equidistantly spaced and by reason of this 65 fact the article receiving loops 13 vary in size whereby pencils or pens of different sizes can be readily and conveniently accommodated, and yet properly supported without the possibility of losing the same. The 70 portions of the tape defining the loops normally lie flat against one side of the plate, but it will be readily understood that through the elasticity of the material, the various portions of the tape can be readily 75 extended to receive a pen or pencil therebetween and the plate 10, and when so extended is tensioned to effectively hold the article in position.

While any suitable means may be employed for securing the plate 10 to the clothing of the user, I preferably make use of substantially Z-shaped fastening elements as shown. The plate 10 is slit transversely from its upper edge adjacent each end of 80 the plate, as at 14, and a portion of the material is curved rearwardly to provide a sleeve 15 for the reception of the vertical portion 16 of the fastening element. Each fastening element is thus pivotally mounted 85 upon the plate, while the short extremity 17 of said element is pointed to permit the same to be readily passed through the clothing of the user. When attaching the plate to the clothing the fastening elements are adjusted 90 so that the short extremity 17 will project rearwardly from the plate at right angles thereto, in which position the said extremities may be readily passed through the clothing. The fastening elements are 95 then swung to position the extremity 17 in parallelism with the plate 10, and the longer extremities 18 extending toward each other. The longer extremities 18 move across the upper edge of the plate and are offset as at 100 19, the offset portions 19 being received in suitable openings 20 whereby the fastening elements are locked in active position, and thereby practically eliminate all possibility 105 of loss of the device.

While it is believed that from the foregoing description the nature and advantages of the invention will be readily apparent, I desire to have it understood that what is herein shown and described is merely illustrative of the preferred embodiment of the invention, and is in no way considered to be restrictive, as various changes in the construction and arrangement of parts may be resorted to when desired as fall within the scope of what is claimed.

What is claimed is:

1. Means for securing a plate to a garment embodying an angular shaped fastening element pivotally mounted upon the plate and adapted to have one end passed through the garment when disposed at a right angle to the plate, the opposite end providing a manipulating means for swinging the aforementioned end in parallelism with the plate subsequent to being passed through the garment.
2. Means for securing a plate to a garment including an angular shaped fastening element pivotally mounted upon the plate and having one end adapted to be passed through the garment when arranged at right angles to the plate, the opposite end of the element providing a manipulating portion for swinging the aforementioned end in parallelism with the plate subsequent to being passed through the garment.

ment, and means for holding said fastening element in active position.

3. Means for securing a plate to a garment including an angular shaped fastening element pivotally mounted upon the plate and having one end adapted to be passed through the garment when arranged at right angles to the plate, the opposite end of the element providing a manipulating portion for swinging the aforementioned end in parallelism with the plate subsequent to being passed through the garment, and said manipulating portion coöperating with means on said plate whereby said element is locked in active position.

4. Means for securing a plate to a garment including an angular shaped fastening element pivotally mounted upon the plate and having one end adapted to be passed through the garment when arranged at right angles to the plate, the opposite end of the element providing a manipulating portion for swinging the aforementioned end in parallelism with the plate subsequent to being passed through the garment, said plate having an opening, and said manipulating portion having an offset extremity adapted to be received within said opening, whereby said element is locked in active position.

In testimony whereof I affix my signature.

HARRY L. WHISINNAND.
